[57] CLAIM

The ornamental design for a surgical instrument, substantially as shown.

DESCRIPTION

FIG. 1 is a side elevational view of a surgical instrument showing my new design;

FIG. 2 is an elevational view of the opposite side thereof;

FIG. 3 is an edge elevational view looking from the left side of FIG. 1, the opposite edge being a mirror image thereof;

FIG. 4 is a bottom plan view of FIG. 1;

FIG. 5 is a top plan view thereof; and

FIG. 6 is a cross-sectional view taken substantially along line 6—6 of FIG. 1.
